UNITED STATES PATENT OFFICE.

HENRY J. OSTER AND HENRY J. KESSELS, OF ETHAN, SOUTH DAKOTA.

FLYING-MACHINE.

1,119,632.

Specification of Letters Patent.

Patented Dec. 1, 1914.

Application filed January 7, 1914. Serial No. 810,912.

To all whom it may concern:

Be it known that we, HENRY J. OSTER and HENRY J. KESSELS, citizens of the United States, residing at Ethan, in the county of Davison and State of South Dakota, have invented certain new and useful Improvements in Flying-Machines, of which the following is a specification, reference being had to the accompanying drawings.

This invention relates to flying machines and more particularly to an aeroplane of the biplane type, the invention having for its primary object to provide improved means for stabilizing or maintaining the equilibrium of the machine in its flight.

The invention has for another of its objects to provide means whereby the machine may be readily steered or guided.

A further object of the invention resides in the provision of the depending spring held wings mounted upon the lower plane which effectually obviate all liability of the machine overturning when heavy wind gusts are encountered.

Our invention has for still another object to generally improve and simplify the construction of heavier-than-air machines of the above type so as to render the same simple and durable in construction, and capable of manufacture at comparatively small cost.

With the above and other objects in view as will become apparent as the description proceeds, the invention consists in certain constructions, combinations and arrangements of the parts that we shall hereinafter fully describe and claim.

For a full understanding of the invention, reference is to be had to the following description and accompanying drawings, in which—

Figure 1 is a perspective view of an aeroplane embodying the present invention in its preferred form; Fig. 2 is a central longitudinal section thereof; Fig. 3 is a horizontal section taken on the line 3—3 of Fig. 2; Fig. 4 is a similar section taken on the line 4—4 of Fig. 2; Fig. 5 is a detail vertical section showing the mounting of the auxiliary stabilizing wings; Fig. 6 is a de-

tail perspective view of a portion of the machine.

Referring in detail to the drawings, 5 and 6 designate the upper and lower planes respectively which are each of cruciform shape in plan. 7 designates the laterally extending arms of each plane arranged at the forward end of the central longitudinally extending body, and 8 indicates the elongated tapering tail portion of each plane. These planes are suitably connected and braced at their edges by means of the truss wires 9. Adjacent the ends of the laterally extending arms of the lower plane 6 and beneath the same, the air reservoirs or cylinders 10 are suitably mounted. Similar longitudinally extending reservoirs 11 are also arranged beneath the tail portion 8 of the lower plane. These cylinders are preferably constructed of aluminum and are adapted to be supplied with air whereby the buoyancy of the machine is materially increased.

Upon the extreme ends of the arms of the lower plane, the depending blades or wings 12 are hingedly mounted along one of their longitudinal edges, the other edges of these blades being flanges as at 13. Coil springs 14 are connected to said blades and to the lower plane 6 and normally act to prevent outward movement of the blades from the ends of the plane. These blades are provided for the purpose of counteracting the tendency of heavy wind gusts striking beneath the lower plane to over-turn the machine.

15 designates the rudder which is suitably mounted upon the rear ends of the tail portions 8 of the planes and is actuated through the medium of the cables 16 which extend from opposite sides of the rudder around suitable guide sheaves or pulleys 17 and are connected to a lever 18 arranged in juxtaposition to the operator's seat which is located between the forward ends of the spaced planes. Collapsible wings or webs 19 are arranged upon opposite sides of the tail portions 8 and are movable at their outer edges along the rods 20 which extend between the ends of the arms 7 and the tail portions 8 of the planes. These webs are normally held

in their collapsed or folded condition by means of the springs 21. The use of these wings is only resorted to when it is necessary to provide additional air contact surface in order to sustain the machine in the air.

Spaced blades 22 are mounted upon a suitable supporting frame 23 extending forwardly from the lower plane 6 of the machine and are adapted to be tilted from their axis by means of a suitable lever 24 connected therewith by a rod 25. These blades are provided for the purpose of causing the machine to ascend or descend to a desired elevation. It will be understood that when it is desired to ascend, the forward ends of said blades are tilted upwardly and upon disposing the blades at a downward inclination, the machine will descend.

An engine 26 of any suitable construction is arranged between the upper and lower planes 5 and 6 and the shaft thereof is connected by a drive chain 27 to a sprocket wheel 28 on a transversely disposed shaft 29. The ends of this shaft are provided with beveled gears 30 for meshing engagement with similar gears 31 upon the ends of the propeller shaft 32. On the forward ends of these latter shafts, suitable propellers 33 are secured. A central longitudinally disposed shaft 34 is also mounted upon the forward end of the machine and is provided with a relatively large propeller 35. A beveled gear 36 on the shaft 29 meshes with a similar gear 37 on the shaft 34 and drives said propeller.

In order to extend the webs or wings 19 to their effective positions, we provide a drum 39 loosely mounted upon the shaft 29 upon which a wire cable 40 is adapted to be wound, said cable extending around suitable guide sheaves and having one of its ends connected to the web 19. A clutch sleeve 41 is fixed upon the shaft 29 and the drum 39 is provided upon one end with clutch teeth. This drum is adapted to be shifted into locked engagement with the clutch sleeve by means of a lever 42 fulcrumed upon the lower plane of the machine and connected by the wire 43 with the operator's lever 44. One end of the drum 39 is also provided with a ratchet 45 to be engaged by a dog 46 mounted upon the lever 42, said dog holding the drum against rotation with respect to the shaft 29. The lever 42 is yieldingly held against movement by means of the spring 47, said spring acting to normally hold the winding drum 39 out of engagement with the clutch sleeve 41. The dog 46 may be readily lifted from engagement with the teeth of the ratchet 45 by means of the lever 48 which is connected to said dog by the wire 49 whereby the springs 21 by contractile force may act to return the webs 19 to their folded or collapsed condition. Ad-

jacent opposite ends of the lower plane 6, 65 the ground wheels 38 are mounted upon the under side thereof to support the machine for movement over the ground in starting its flight.

From the foregoing, it is thought that the construction and arrangement of the several parts of our improved aeroplane will be clearly and fully understood. By the provision of planes of the particular form illustrated in the accompanying drawings, 75 and the additional sustaining webs 19, the machine will be properly sustained at any elevation in very light air currents. The use of the depending wings or blades 12 effectually prevent disaster by over-turning 80 of the machine and materially increase the element of safety. The machine as a whole is very simple in its construction, light in weight and capable of navigating the air under unfavorable conditions. 85

It will be understood that while we have above described the preferred construction and arrangement of the several elements of our invention, the machine is nevertheless susceptible of considerable modification 90 therein and we therefore reserve the right to resort to all such legitimate changes as may be fairly embodied within the spirit and scope of the invention, as claimed.

Having thus described the invention, 95 what is claimed is:

1. In an aeroplane, spaced parallel planes each of cruciform shape in plan, propelling means mounted between said planes, collapsible webs arranged upon opposite sides 100 of the planes, steering means, and ascending and descending blades adjustably mounted upon the forward end of the machine.

2. In an aeroplane, upper and lower spaced planes each having forward laterally extending arms and rearwardly extending tail portions, propelling means mounted between the planes, means for steering the machine, and spring held wings depending from the ends of the arms of the 110 lower plane.

3. In an aeroplane, upper and lower planes each having forward laterally extending arms and a central rearwardly extending tail portion, collapsible webs arranged between the arms and the tail portion of the machine, springs normally holding the webs in collapsed condition, propelling means for the machine, means for steering the machine in its flight, and wings depending from the ends of the arms of the 115 lower plane. 120

4. In an aeroplane, upper and lower planes each having forward laterally extending arms, and a rearwardly extending 125 tail portion, air reservoirs upon the under side of the lower plane, propelling means arranged between the planes, means for di-

fecting the flight of the machine, wings hingedly mounted upon the ends of the arms of the lower plane and depending therefrom, and springs yieldingly holding said wings against movement with respect to the plane in one direction.

In testimony whereof we hereunto affix

our signatures in the presence of two witnesses.

HENRY J. OSTER.

HENRY J. KESSELS.
